CARVING KNIFE

Donald A. Wallace, Croton-on-Hudson, N.Y., assignor
to H. E. Laufer Company, New York, N.Y., a corpora-
tion of New York

Filed Feb. 5, 1962, Ser. No. 68,659

Term of patent 14 years

(Cl. D95—3)

FIG. 1

FIG. 2

FIG. 3

FIG. 4

FIG. 5

FIGURE 1 is a side elevational view of a carving knife showing my new design.

FIGURE 2 is a bottom view thereof.

FIGURE 3 is a top plan view thereof.

FIGURE 4 is a transverse sectional view upon the line 4—4 of FIGURE 1.

FIGURE 5 is a transverse sectional view upon the line 5—5 of FIGURE 1.

The characteristic features of my design reside in the carving knife disclosed of the particular handle portion formed of plastic plaques having metallic bands on each side thereof connecting the end cap or piece with the integral blade supporting shank in combination with the relatively long and narrow blade portion whose blunt edge lies in the plane of the handle, all as shown.

I claim:

The ornamental design for carving knife, as shown and described.
